H. F. OBERGFELL

AUTOMATIC SWITCH MOUNTING

Filed May 11, 1925

Herbert F. Oberfell
Walter Dorn

UNITED STATES PATENT OFFICE.

HERBERT F. OBERGFEILL, OF RIVER FOREST, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC SWITCH MOUNTING.

Application filed May 11, 1925. Serial No. 29,298.

The present invention relates in general to automatic switch mounting, more especially to the mounting arrangement of certain of such switches that are used in 5 automatic telephone systems.

Specifically, the invention relates to an improved method of mounting the non-numerical line switch and banks of an automatic telephone system, which permits 10 greater ease in assembly, adjustment and maintenance thereof.

The drawings, comprising Figs. 1 and 2, show sufficient details of the switch mountings to illustrate the present invention.

15 Fig. 1 shows a section of a Keith line-switch board of the Strowger system, as seen from the top, with the details of the mounting of the line switch and banks in accordance with this invention. This line-switch board is the one hundred line plunger type line-switch board of the Strowger automatic telephone system, of the general type 20 shown in Fig. 86 on page 107 of the second edition of Automatic Telephony by Smith and Campbell. A further idea of the details 25 of this line-switch board may be gained from Fig. 45 on page 47 of the above reference in which figure is shown the master switch, line switch, banks and jack springs 30 that will be referred to hereinafter. The bank B of Fig. 1 is shown again in more detail in Fig. 44 on page 46 of the above reference.

Fig. 2 is the elevation of a section of 35 the mounting panel 31' of Fig. 1, showing the details of the bank mounting rod 33' and bank mounting clamps 38 that will be pointed out in detail hereinafter.

The line switch LS of Fig. 1 is a plunger 40 type line switch such as is shown in detail in my co-pending application Serial No. 13,046, filed March 5, 1925. Briefly, the line switch LS is a non-numerical switch individual to the line of an automatic telephone 45 system, whose principal duty is to automatically operate, in response to the initiation of a call by the removal of the receiver from the telephone, to connect the calling line to an idle selecting switch, through the medium of the bank B. Co-operating with the line switch LS is the master switch, 50 shown in Fig. 42 of the above reference, which through the medium of the line switch guide shaft 44 of Fig. 1 keeps the

plunger 6 of the line switch standing opposite an idle bank contact. In performing this function the master switch swings the line switch guide shaft 44 about an axis which extends through the plunger bearing pin 22 of the line switch LS, in a manner 55 which can be very readily seen from the above reference, Fig. 45. The mounting bracket which determines the location of this plunger guide shaft 44 is shown at the top of Fig. 45, and it will be noted that 60 this bracket is rigidly fastened to the mounting plate, such as 31 and 31' of Fig. 1; that is, the axis of the guide shaft is definitely located with respect to the face of the mounting plate. Therefore, it is readily 65 seen that if the plungers 6 are to move freely through the bank B under control of the guide shaft 44, the bank B and the bearing pin 22 of the plunger must be carefully located with respect to the mounting brackets 70 75 31 and 31'. Moreover, since the bearing pin 22 permits the plungers 6 to move only in one plane, the lateral axis of the bank 36 must lie exactly at right angles to this bearing pin 22. 80

Accordingly, one of the objects of my invention is to provide a new and improved method of mounting the bank B in the frame, so that it will be definitely located with respect to the axis of rotation of the 85 master switch guide shaft.

In the process of manufacturing such a line-switch board, the line switches are assembled and adjusted as a unit independent of the banks. In adjusting these line 90 switches the bearing pin 22 is definitely located with respect to the mounting bracket 1' of the main switch base 1 by adjusting the back stop screw 10 and the bearing pin 15 as set forth in the above mentioned application. The line switch then forms a 95 completely adjusted unit and is ready to be mounted upon the line-switch board.

Assume for the moment that the banks 36 are properly aligned with respect to the 100 mounting plates 31 and 31' and the axis which passes through the pin 22 of the line switch, it is still necessary to provide means for adjusting the line switch itself so that the bearing pin 22 will coincide with the 105 above mentioned axis.

Accordingly, a further object of this invention is to provide an improved and

simplified means of mounting the plunger type line switch on the switch board upright, a means that provides for easy adjustment and alignment of the switch.

5 Having thus described the objects of my invention, I will now proceed with a detailed description of the bank mounting of my invention.

The bank assembly B consists of a bank of 10 terminals 36 supported by a mounting strip 35, and in the manufacture of the bank alignment is made with respect to this mounting strip 35. In mounting the bank in the line-switch board, it is therefore necessary only to align the mounting strip 35 with respect to the face of the mounting plates 31 and 31' in order to have the banks properly aligned. For this purpose I provide the bank mounting rods 33 and 33' in 15 which I have cut grooves 37 to receive the mounting plate 35. These grooves are accurately machined so that the mounting plates 35 and 35' of Fig. 2 will be correctly spaced vertically with respect to each other 20 when inserted in the groove 37. The bank mounting plates 35 are held into engagement with the mounting rods 33 and 33' by means of the clamp 38, so that the entire bank assembly can be assembled as a unit before 25 being placed into the line-switch board upright. In order to space the banks in and out with respect to the mounting face of the uprights 31 and 31' I provide the spacing collars 32 and 32' which are accurately machined and which space the bank mounting rods 33 and 33' definitely with respect to 30 the mounting plates 31 and 31', respectively. The mounting plates 31 and 31' are drilled to take a machine screw which passes 35 through these plates, through the spacing collars 32 and 32', and through the bank mounting rods 33 and 33', being threaded into the latter. In the line-switch board of the above reference, twenty-five banks would 40 be mounted on one pair of bank mounting rods and the assembly held to the board by means of eight machine screws such as 34 and 34', four being placed into and through each of the bank mounting rods. The holes 45 drilled in the mounting plates to receive the bank mounting screws 34 and 34' are accurately drilled and counter-sunk so that when the eight screws are drawn up tight the assembly of twenty-five banks is accurately aligned, vertically and in both ways horizontally. The mounting screws 34 extend 50 through the bank rods 33 and the bank mounting clamp 38, the latter being held in place by a nut which not only serves to hold the bank in place, but also to lock the bank mounting screw. The switch mounting clamps 38 which do not come in such a space 55 as to be held on by the bank mounting screw 34 are attached to the bank mounting rod 60 33 by the stud screw 38' as shown in Fig. 2.

Having thus assembled the banks in the line-switch board, they are properly aligned and are ready to receive the switches, the mounting of which will now be described. The mounting plate 1' of the switch LS is 70 drilled to pass over the heads of screws 43, and slotted to engage the flanges of those screws as the switch is slid into place. The insulated screws 43 are arranged to fit into these slots with a minimum of vertical play, 75 thus minimizing the vertical alignment of the switch after it is mounted on the line-switch board. It is the established practice to insulate these line switches LS from the mounting frame, and I have, therefore, provided the insulating strip 40 which extends over the entire face of the mounting plate 31 to insulate the line switches therefrom. In mounting the line switch, it is therefore only necessary to insert the male jack of the 80 line switch into the female jack 41 which is mounted on the mounting plate 31; slip the screws 43 through the slot and the base of the line switch and tighten them up after the line switch has been adjusted correctly 85 right and left so that the bearing pin 22 is in correct alignment with the axis of the master switch. Very little up and down adjustment, that is adjustment parallel to the master switch guide shaft 44, is necessary because of the close fit between the insulated screws 43 and the slot in the base 90 of the line switch. The screws 43 being insulated aid the insulating strip 40 in preventing the frame of the switch 1 from coming 95 in contact with the mounting plate 31.

It is easily seen that I have devised a new and efficient method of mounting the banks and switches of the class described. The bank mounting requires no adjustment to 105 properly align the banks, and the line switch mounting requires only adjustment in one direction, thus providing a method which is inexpensive because of the small amount of labor required to properly align the switches 110 and switch banks.

Having thus described my invention, what I consider new and desire to have protected by Letters Patent is pointed out in the appended claims.

115 What is claimed is:

1. In an automatic telephone system, a line switch bank and a line switch arranged to plunge into said bank to establish connections therein, a common mounting plate on 120 opposite sides of which are mounted said line switch and bank, said bank being mounted by means of a grooved rod into which a member of the bank slips and by means of which the bank is located in one 125 direction, and a means comprising a spacing washer and machine screw for locating said rod in another direction with respect to said mounting plate.

130 2. In an automatic telephone system, a

plurality of line switch banks each having a mounting plate containing two U-shaped slots, two mounting rods each containing a plurality of grooves into which the U-shaped slots of said bank mountings snugly fit, a plurality of clamps arranged to hold said banks on said rods, a switchboard mounting plate, and means comprising machine screws and spacing washers for mounting said bank assembly on said mounting plate.

3. In a telephone system, a mounting frame for supporting a plurality of switches and their co-operating switch banks, said frame consisting of a pair of uprights, a rod mounted on each upright on one side thereof spaced equidistant from the uprights and each having a plurality of grooves around the rod, each groove in the same plane as the corresponding groove on the other rod, a series of switch banks having forked ends registering with a groove in each rod, a washer engaging each pair of banks to retain the banks in the grooves, and a series of switches mounted on each upright each having an arm registering with one of said banks.

4. In a telephone system, a plurality of automatic switches, a bank associated with each of said switches, a mounting frame for said switches and banks containing upright members, said switches being mounted on one side of said uprights and insulated therefrom, said banks being mounted on rods and spaced thereon by means of grooves in said rods into which forked members of said banks fit, said assembly of banks and rods

being mounted on the opposite side of said uprights, one of said rods being held parallel to the switch mounting face of each of said uprights by means of machine screws 40 and spacing washers.

5. A mounting for electrical devices comprising a plurality of devices fixed, in grooves upon a plurality of rods and definitely located thereby with respect to each other and to said rods, a mounting plate and means for fastening said rods on and locating them with respect to said plate to locate said devices with respect thereto.

6. A mounting for electrical devices comprising rods containing grooves spaced at definite intervals along it, projections on said devices having forked ends registering with certain of said grooves, a mounting plate to which said rods are attached and from which they are definitely spaced by suitable means, said rods, spacing means and projections cooperating to definitely locate said devices with respect to said mounting plate.

7. A mounting for electrical devices comprising a plurality of rods each containing a plurality of grooves, a plurality of projections on said devices containing forked ends which register with said grooves to locate said devices with respect to each other on said rods and means for retaining said forked ends in said grooves.

In witness whereof, I hereunto subscribe my name this 7th day of May, A. D. 1925.

HERBERT F. OBERGFELL.
